(57) **CLAIM**

We claim the ornamental design for inverter, as shown and described.

DESCRIPTION

FIG. 1 is a top perspective view of the inverter showing my new design.

FIG. 2 is a bottom perspective view thereof.

FIG. 3 is a top view thereof.

FIG. 4 is a bottom view thereof.

FIG. 5 is a front view thereof.

FIG. 6 is a back view thereof.

FIG. 7 is a right side view thereof; and,

FIG. 8 is a left side view thereof.

1 Claim, 6 Drawing Sheets

FIG. 1

FIG. 2

FIG. 3

FIG. 4

FIG. 5

FIG. 6

FIG. 7

FIG. 8
